A. CORDUAN.
NEEDLE THREADER FOR SEWING MACHINES.
APPLICATION FILED APR. 30, 1919.

1,350,592.

Patented Aug. 24, 1920.

UNITED STATES PATENT OFFICE.

ADOLPH CORDUAN, OF ROSELLE PARK, NEW JERSEY.

NEEDLE-THREADER FOR SEWING-MACHINES.

1,350,592.

Specification of Letters Patent. Patented Aug. 24, 1920.

Application filed April 30, 1919. Serial No. 293,618.

To all whom it may concern:

Be it known that I, ADOLPH CORDUAN, a citizen of the United States, and a resident of Roselle Park, county of Union, and State 5 of New Jersey, have invented certain new and useful Improvements in Needle-Threaders for Sewing-Machines, of which the following is a specification.

This invention relates to an improved 10 needle threader of the type that is attached to a sewing machine and which is swung down into position to thread the needle when desired, and is returned to an inoperative or out-of-the-way position when released.

15 The invention is designed to provide a needle threader of this kind which is adjustable in several directions so that after being attached to a sewing machine it can be regulated so that when swung into position the 20 threading hook enters the eye of the needle without unnecessary strain on either the needle or the hook.

The invention is further designed to provide a needle threader of this kind which 25 has the threading hook held by a securing means that can be easily released and a broken hook can be quickly removed and replaced by another when necessary.

The invention further provides for a 30 threading device of this kind in which the hook is so disposed that it does not carry the loop of the thread to a point beyond the needle after the needle is threaded, so that manual removal is not necessary. In other 35 words, the thread is carried through the eye of the needle in threading and released after material length has been carried through and the thread is not carried by the hook up to the inoperative position of the threader.

40 In factories where these devices are used and but one operator is taking care of many machines, this is a factor that is desirable since it is not necessary to take the time to release the loop from the threading hook.

45 The invention is illustrated in the accompanying drawing, in which Figure 1 is a front view of the bottom part of the head of a sewing machine, the threader being shown in elevation and the lower part of the 50 sewing machine needle being shown in section. Fig. 2 is a side view of the construction shown in Fig. 1. Fig. 3 is a bottom view of a bracket which is part of the threading device and by means of which it is se-

cured to the presser foot post of the machine. Fig. 4 is a section through the threading hook and its holder taken on line 4 in Fig. 1, and Fig. 5 is a section through the joint by means of which the arm of the threader is pivoted to the bracket. 55 60

For the purpose of illustration I show one form of threading device, but it will be understood that slight modifications can be made in the disposition and formation of the parts without departing from the scope 65 of the invention.

In the drawing 10 indicates the head of the sewing machine, 11 is the needle bar and 12 is the needle. 13 is the presser foot bar on which the presser foot 14 is suspended, 70 these parts as enumerated all being old and being in substantially the same relative positions in all sewing machines. My threader is secured to the presser foot bar 13 by means of a bracket, the bracket comprising 75 two members 15 and 16, the member 15 having a sleeve 17 which fits around the presser foot bar and has a flat plate 18 on which the plate 19 of the member 16 is adapted to slide, the plate 19 having a disk 20 thereon 80 which co-operates with a similar disk, as will be hereinafter described.

The two members 15 and 16 are adapted to be secured in different adjusted positions, 85 one form of fastening being shown and consisting of the screws 21 which pass through the slots 22, these slots being long enough to permit a sliding adjustment when the screws 21 are unscrewed, the screws when tightened holding these two members 15 and 90 16 in any desired adjusted positions. The bracket can swing freely on the bar 13 and is usually supported by a suitable friction device, such as the spring 23, which abuts at one end on the under side of the member 95 15, and abuts at the other end on a collar 24 which is fastened in place by suitable means, such as the screw 25.

Secured to the bracket is an arm 26 which 100 preferably is made so that it can be adjusted as to its length, and for this purpose it is made of two members 27 and 28, the member 27 having a disk portion 29 which abuts against the disk portion 20 of the bracket, these disks 20 and 29 usually being bulged 105 sufficiently to receive a spring 30, which has one end, as 31, projecting through one end, and the other end, as at 32, projecting

through the other disk so that the arm is under tension of the spring 30, the two disks being held so that the arm can swing on the bracket by means of a suitable pin or rivet 33.

- The members 27 and 28 are arranged telescopically. In the form shown, the member 27 is provided with a slot 34, and a screw 35 passes through the slot and is in screw-threaded engagement with the member 28, and in this way the arm can be adjusted as to its length. The end of the arm 28 is provided with a finder 36 which swings on a stud 37 which is fastened to the end of the member 28, the finder being adapted to have a limited swinging movement, being limited in one direction by the abutment 38 and in the other direction by the abutment 39. The finder 36 has one edge tapered, as at 40, to permit the insertion of the thread in the hook 42, and its end 41 is rounded so as to give smooth surfaces in all directions, and alongside of the inclined or tapered side 40, and projecting slightly beyond it, is the said threading hook 42 with the extremity 43 formed with a slight notch or depression to receive the thread, the hook 42 having a pair of openings which fit over the studs 44, these studs being secured to the finder 36.
- 30 A spring 45 is fastened so as to swing with the finder 36 and is adapted to bear with a spring pressure against the threading hook 42 and hold it in position, the spring also having openings which fit over the studs 44.
- 35 The end 46 of the flat spring 45 is bent away enough from the hook to provide for getting the finger nail under it so that it can be pulled out, and in this way a broken hook can be withdrawn and a new hook installed,
- 40 the release of the spring permitting it to snap back so as to hold the hook in position. The forward end of the finder 36 is slightly offset so that when the finder bears against the side of the needle, the threading hook is in line with the eye 47 of the needle 12.
- 45 When the device is installed on a machine, the adjustment to the front and rear can be made by unscrewing the screws 21 slightly and moving the member 16 until the hook 42 is in line with the eye of the needle, and by screwing up the screws 21 when the adjustment is made, the parts are held in this position. By means of the slot 34 and the screw 35, the length of the arm can be adjusted so as to bring the threading hook approximately in position to enter the eye of the needle when the arm is swung down to the position shown in dotted outline in the lower part of Fig. 1. It is noted that, in the disposition of the parts, when the end of the arm is swung downward, the curved part of the threading hook, that is, the back of the part 43, is uppermost, and if this curved part engages the upper edge of the eye of the needle, it is swung by such

slightly rounded part so that the entrance of the hook into the eye of the needle is made easy.

The abutment 38 prevents excessive inward movement of the finder 36, and consequently the threading hook, and when the arm is swung downward by the thumb and first finger of the hand, in which manner it is usually done, the hook is brought in nearly perfect alignment with the eye of the needle, 75 and as the end of the hook passes beyond the vertical plane passing through the center of the pivot 33, the threading hook continues to pass substantially horizontally because its upper edge is bearing against the upper 80 wall of the eye of the needle and the movement of the threading hook is substantially horizontal and no longer in a curved line.

When the thread is carried under the hook 42, the hook is released and the spring 30 85 snaps the arm 28 around to the position shown in full lines in Fig. 1, and this pulls the loop of the thread with it. Whenever released, the arm swings to its uppermost position, and to prevent the hook and the finder engaging goods passing under the head of the sewing machine, the finder can be swung upward, as shown in dotted outline in the upper part of Fig. 1, so that it lies fairly close against the head of the sewing 95 machine. When the arm 26 swings upward it can also be arranged to swing to the rear, so that its normal position is in back of the head of the sewing machine, by having the ends 48 and 49 of the spring 23 secured in 100 suitable holes in the bracket and in the collar 24, respectively, the hole 50 in the bracket and a similar hole in the collar 24 acting to normally twist the bracket, and consequently the arm, around to a position 105 in rear of the sewing machine head.

When it is swung forward, the bracket is limited in its swinging movement usually by engagement with a stop, and in the form shown the plate 18 of the member 15 abuts 110 or hits against the needle bar 11 so that when the threader is swung around to the front until it stops, it is in position with its threading hook in the same vertical plane as the eye of the needle, so that when the 115 arm 26 is swung downward, the threading hook enters the eye of the needle without the necessity of the operator making repeated efforts to find the eye of the needle with the threading hook.

120 In order to allow for the space between the presser foot bar 13 and the needle, the parts are offset, in the form shown this offset being shown at 51 in the arm 28, but it will be understood that other parts can be 125 offset to bring the threading hook over to a position where it is in line with the eye of the needle.

130 If desired, one of the disks, preferably the disk formed as part of the member 16,

is provided with a projection 52 that has an opening 53, one edge of which is sharpened and which has a converging entrance slot 54 so as to form a thread cutter.

5 It will be understood that the collar 24 can be adjusted to make the tension of the spring such as to normally hold the threader in the position shown in the drawing, that is, in its forward position ready to be swung 10 down to thread the needle.

With the arrangement shown herein of mounting the member or bracket on the presser foot bar, the raising or lowering of the presser foot bar does not alter the position 15 of the bracket, since it is held by the pressure of the spring in position against the bottom of the head of the sewing machine, and whether the presser foot bar is down or up makes no difference so far as 20 the vertical position of the threader is concerned. It will be understood that a particular position for the needle is preferred, the parts being adjusted so that the needle is in position to be threaded when it is at 25 its highest point in its path of travel.

I claim:

1. A needle threader for sewing machines comprising a threading hook secured on the end of an arm swinging in a vertical plane, 30 a bracket to which the arm is secured, and means for supporting the bracket so that it can swing in a horizontal plane.

2. A needle threader for sewing machines comprising a threading hook secured on the end of an arm swinging in a vertical plane, a bracket to which the arm is secured, means for supporting the bracket so that it can swing in a horizontal plane, and means for 35 limiting the swinging of the bracket to 40 bring the threading hook in the same plane as the eye of a needle in the machine.

3. A needle threader for sewing machines

comprising a vertically swinging arm, a horizontally swinging bracket, a spring connection between them to normally hold the 45 arm in raised position, the arm being adjustable as to its length, and a threading hook on the free end of the arm and mounted so as to have a limited swinging movement in a plane parallel to the plane of the swinging 50 movement of the arm.

4. A needle threader for sewing machines comprising a vertically swinging arm, a bracket to which the arm is pivoted, the bracket having a sleeve thereon to surround 55 the presser bar of the sewing machine, a collar on the presser bar, a spring abutting on the collar and the bracket, and a threading hook mounted on the end of the arm and pointing in a plane parallel to the plane in 60 which the arm swings.

5. A needle threader for sewing machines comprising a bracket made of two members slidably arranged and having means for securing them in adjusted positions, one member being adapted to be secured to the presser bar of a sewing machine, and the other member having a pivot plate, an arm consisting of two members, one member having a pivot plate to be attached to the pivot 70 plate of the bracket, the members of the arm being slidably secured together and having means for securing them in adjusted positions, a guide pivoted to the free end of the arm, the arm having a stop so that the 75 swinging of the guide is limited, and a threading hook secured to the guide and substantially parallel thereto, the guide being substantially parallel to the plane in 80 which the arm swings.

In testimony that I claim the foregoing, I have hereto set my hand, this 26th day of April, 1919.

ADOLPH CORDUAN.
